UNITED STATES PATENT OFFICE.

JOHN CLIFFORD WHITRIDGE, GEORGE TEWKSBURY JOHNSON, AND HARRY HAMILTON WOLFE, OF COLUMBUS, OHIO, ASSIGNORS TO THE BUCKEYE STEEL CASTINGS COMPANY, OF COLUMBUS, OHIO.

CAR-COUPING DEVICE.

Original application filed March 22, 1923, Serial No. 626,934. Divided and this application filed November 5, 1923. Serial No. 672,856.

To all whom it may concern:

Be it known that we, JOHN C. WHITRIDGE, GEORGE T. JOHNSON, and HARRY H. WOLFE, citizens of the United States, and residents 5 of Columbus, in the county of Franklin and State of Ohio, have invented certain new and useful Improvements in Car-Coupling Devices; and we do hereby declare the following to be a full, clear, and exact description 10 of the invention, such as will enable others skilled in the art to which it appertains to make and use the same.

This invention relates to improvements in car coupling devices, and more particularly 15 to such as contemplate the connecting of an automatic coupling with a coupling of the hook type,—this application being a division of application for patent filed by J. C. Whitridge, G. T. Johnson, H. W. Stertzbach and H. H. Wolfe March 22, 1923, and designated by Serial No. 626,934.

An object of the present invention is to provide simple and efficient connecting 20 means between couplings of the automatic and hook types, which connecting means shall be flexible and capable of such vertical folding when the cars come together as not to interfere with the buffing relation of the cars.

With this and other objects in view, the 25 invention consists in certain novel features of construction and combinations of parts as hereinafter set forth and pointed out in the claims.

In the accompanying drawings; Figure 1 is a plan view showing an embodiment of 30 our invention, and

Figure 2 is a side view.

A car coupling of the M. C. B. automatic 35 type is represented at 1 and 2 indicates a coupling of the hook type.

The knuckle 3 of the coupling 1 is provided near its free end with a vertical hole 40 for the accommodation of a vertical pin 4 and said knuckle is provided in its free end with an intermediate transverse slot 5 which intersects the hole through which the pin 45 passes.

The connecting devices between the two 50 couplings includes a flat plate 6 having an opening through its rear portion, said plate

entering the slot 5 in the knuckle and pivotally engaging the vertical pin 4. The plate 6 is provided with rearwardly projecting hooks 7, 7 at its outer or forward corners 55 and these hooks are engaged through eyes 8 at the ends of a substantially V-shaped link 9 which, in turn, is engaged at its bight with a vertical eye 10 at one end of a horizontal link 11. This link 11 is approximately 60 trapezoidal in form and its inner wall corresponds approximately to the cross-sectional contour of the hook coupling. It will be noted that the eye 10 forms a narrow central extension of the link 11 so that the eye may 65 fit closely in the acute angle presented by the V-shaped link 9 while the body of the link 11 may engage closely around the hook coupler. The possibility of accidental separation of the parts is thus minimized 70 while they may readily accommodate the relative movement of the cars.

When the cars come together, the links 9 and 11 fold downwardly between the couplings and therefore do not interfere with 75 the buffing action of the cars.

Having fully described our invention what we claim as new and desire to secure by Letters-Patent, is:

1. In a device of the class described, the 80 combination of an automatic coupler including a knuckle, and a vertical pin in the free end portion of the knuckle, a hook coupler, an eye engaged around said pin, and a foldable connection between said eye and the 85 hook coupler, said connection including a V-shaped link carried by the eye and a trapezoidal link engaged with the hook coupler and provided at its outer end with a relatively narrow central extension engaged in the apex of the V-shaped link.

2. In a device of the class described, the 90 combination of an automatic coupler including a knuckle, and a pin mounted vertically in the free end portion of the knuckle, a 95 hook coupler, a plate pivotally engaged on the pin and within the knuckle, hooks on the opposite edges of said plate in front of the knuckle, a V-shaped link having its ends engaged with said hooks, and a link connection 100 between said link and the hook coupler.

3. In a device of the class described, the

combination of an automatic coupler including a knuckle, and a pin mounted vertically in the free end portion of the knuckle, a hook coupler, a plate pivotally engaged on 5 the pin and within the knuckle, hooks on the opposite edges of said plate in front of the knuckle, a V-shaped link having its ends engaged with said hooks, and a link connection between said link and the hook coupler, said 10 link connection comprising a horizontal link to receive the hook coupling and a vertical

eye on said link to engage in the V-shaped link.

In testimony whereof, we have signed this specification in the presence of two subscribers. 15

JOHN CLIFFORD WHITRIDGE.
GEORGE TEWKSBURY JOHNSON.

HARRY HAMILTON WOLFE.
